UNITED STATES PATENT OFFICE.

JULIUS E. KARL, OF PEORIA, ILLINOIS.

APPARATUS FOR AUTOMATICALLY PAINTING ARTICLES IN BULK.

Specification of Letters Patent. Patented Sept. 20, 1921.

1,391,388.

Application filed October 4, 1918. Serial No. 256,894.

To all whom it may concern:

Be it known that I, JULIUS E. KARL, citizen of the United States, residing at Peoria, in the county of Peoria and State of Illinois, have invented certain new and useful Improvements in Apparatus for Automatically Painting Articles in Bulk; and I do hereby declare that the following is a full, clear, and exact description of the invention, 5 which will enable others skilled in the art to which it appertains to make and use the same.

This invention relates to an apparatus for painting articles or otherwise covering them with a protecting material. The invention relates more particularly, however, to the treatment of a bulk or quantity of manufactured materials, such as castings or parts made of wood or other material entering into 10 the manufacture of machines.

The main object of my invention is to coat in bulk, quantities of castings or wooden parts entering into the manufacture of machines, while piled on trucks or other carriers, which castings or parts while piled upon such trucks or carriers are in most cases separately dipped into the paint or other coating material.

Another object is to submit to treatment of 30 a protecting material, such as a paint, truck loads of castings or parts made of wood or other material entering into the construction of machines without removing the same from their trucks.

Another object is to provide an apparatus 35 which will be automatic in its action, in that truck loads of the materials to be treated upon being placed within the zone occupied by the apparatus will be automatically coated and drained and then removed from such zone.

Other objects and advantages will appear in the following specification.

To the end that my invention may be understood, I have provided the accompanying drawings, wherein,

Figure 1 is a longitudinal sectional elevation of a structure showing my apparatus;

Fig. 2 is a plan of certain portions of the 50 same, somewhat enlarged;

Fig. 3 is an elevation of a loaded truck and certain elements used for automatically moving the same;

Fig. 4 shows, in perspective, certain operating parts;

Fig. 5 is a transverse section of an enclosure or housing and a track and a truck mounted upon the latter;

Fig. 6 is a view similar to that shown in Fig. 5, as to said tracks, and truck, showing a different position of the latter;

Fig. 7 shows, in perspective, a portion of the tracks shown in Figs. 5 and 6, and a guard rail;

Fig. 8 is an elevation of a paint-distributing pipe-system showing two tilted positions of a pair of trucks thereunder;

Fig. 9 is an elevation of one of the wheels of a truck, and a stop device therefor;

Fig. 10 is a longitudinal sectional elevation, similar to Fig. 1, of a modified form of apparatus;

Fig. 11 is a plan of certain track portions, a truck mounted thereon, and a drag device for the latter;

Fig. 12 is an elevation, in transverse section, of part of the apparatus shown in Fig. 10; and,

Fig. 13 is an elevation of a track portion and a stop-device for a truck-wheel.

Heretofore it has been customary, especially with regard to parts of wood entering into the construction of machinery, to dip such parts by hand, such hand-treatment being thought necessary in order to thoroughly cover such parts with the coating material and from the fact also of there being no method devised for the purpose of dipping the entire bulk. As the hand method is expensive in that much time and labor is involved, I have devised the apparatus herein which has been found to yield satisfactory results in the treatment of entire truck loads without handling the materials in any way and that will be treated in an entirely automatic manner.

In the first nine figures 1 represents the two rails of a track which, in the present instance, is shown overhanging an excavation, such as 2 in which is stationed a suitable trough 3 for containing the coating material over which trough said track also extends, it being understood, however, that the trough may be built above ground and the track extended up over it if desired, although the method described and shown is preferable since most convenient.

Covering said trough 3 is a housing 4 which is provided merely as a protection against fire being communicated to the paint

in said trough, said housing being provided with doors 5 at each end to automatically open and close in the movement of the trucks, approaching and leaving said housing. The mechanism for operating the doors is not shown in Fig. 1 since to do so would unnecessarily complicate that figure and make it difficult to read. This mechanism is shown, however, in Figs. 2 and 4 wherein 10 6 and 7 indicate two rock shafts, one outside and the other inside the housing 4 beneath the rails 1. The shaft 6 which is outside has at each end an upturned arm 8 each of which is connected with one of the doors 5 by means of rods 9, said shaft 6 having an 15 upstanding arm 10. The shaft 7 also has an upstanding arm 11 and at one end has a depending arm 12 connected by a rod 13 with an arm 14 which uprises from the said 20 shaft 6.

It will now be understood that by moving the arm 10 in the direction of the dart in Fig. 4 that the rods 9 will operate to open the doors 5 inward to the position shown in Fig. 1 allowing a truck to pass through and that a movement of the arm 11 in the same direction will operate to return the doors to the closed position since the movement of the shaft 7 in this direction will reverse the 30 movement of the shaft 6.

Though not shown, the doors 5 at the opposite end of the housing are operated in the same manner but necessarily are opened outward away from an approaching truck, as that truck after treatment is passing from 35 said housing.

As shown in some of the figures, the truck indicated at 15 is provided with a pair of wheels 16 at each end, and in the center or 40 middle with a wheel 17. The wheels 16 run upon the rails 1 while the said wheel 17 is designed to travel in a grooved rail 18 located between the rails 1. By this arrangement or any other preferred one it is 45 designed that said wheels 16 will be retained upon their rails.

Lying between the rails 1 is a drag-chain or belt 19, see Fig. 2, which runs over 50 sprocket wheels 20 and 21, Fig. 1, the upper stretch of said chain being guided over a supporting sprocket at 22, whereby the said upper stretch will be held up between the rails 1 for a purpose now to be described.

At one or both ends of the truck 15 there 55 is a depending portion 23, for example, which hangs close to the rails and on said chain or belt 19 is an uprising finger 24 which in its travel with the chain is designed to engage said portion 23 for propelling said 60 truck. Other wheels corresponding to 22 may, of course, be used where desired.

25, Fig. 1, is a drive-chain driven from any suitable power source by which the chain 19 may be continuously driven.

65 A loaded truck moved along upon the

track 1 to the position shown at the right in Fig. 1 above the chain 19 is in position to be engaged by the lug 24 in the travel of the chain or belt and it is preferable after having placed the truck in this position to provide some means for preventing it moving out of the path of travel of the finger 24. This is accomplished by providing a trip device shown clearly in Fig. 9. It may consist of a dog 26, for example, pivoted upon 70 one of the rails 1, and held by a spring 27, normally in the path of one of the wheels 16 through the aid of a stop 28 on the said rail, for example. Movement of the wheel 16 in the direction of the dart in said Fig. 9 will 75 carry the dog downward out of the way but after the wheel has passed said dog will be moved to its upright position by the spring whereupon the wheel in a retrograde movement which may be occasioned by a backward slope of the rail, as shown in Fig. 1, will lodge against it.

It is preferred, as shown in said Fig. 1, to thus incline the track 1 upwardly toward and into the housing 4 and thence downwardly to a slightly lower level and thence again upwardly toward the opposite end of the housing. The purpose of this will be understood later herein.

The bottom of the trough 3 preferably 95 slopes downwardly from each end toward a middle lowermost portion 29 in which is mounted an agitator 30 operated by a drive-chain 31 from any suitable source of power at 32, for example, while above said portion 100 and said agitator, is a pump 33 of the rotary type, for example, driven from the agitator 30 for instance, through a chain 34.

35 is a pipe uprising from the pump and 105 extending longitudinally throughout a portion of the housing 4 and terminating in a series of depending nozzles 36, 37 and 38 out of which the painting or coating material issues in unbroken streams from said pump 33.

39 is a chain or belt similar to 19 described, which runs over wheels 40, 41, one of which may be driven from the power source at 32, for example, by means of belts 42 and 43.

44 is a supporting wheel or pulley for the upper stretch of this chain or belt to hold that stretch in line with the track 1 as has been previously described with reference to said belt-chain or belt 19, and this member 120 39 is provided with a finger 45 corresponding to 24.

It is observed in Fig. 2 that these two chains or belts 19 and 39 extend somewhat beyond one another at the supporting wheels 125 or pulleys 21, 40. By this arrangement, in the movement of the chain 19, a truck shown at the left of Fig. 1 will be carried to a point where the finger 24 will pass off of the depending portion 23 of said truck as in 130

Fig. 3, the finger 45 of the belt or chain 39 being in position to engage said depending portion and carry the truck outside the housing.

5 At this point of the track also is a dog already described in connection with Fig. 9. The chain or belt 19 is designed to travel at a definite rate of speed to move the truck in the direction of the arrow, Fig. 1, into the 10 housing beneath the depending nozzles 38 from which the paint or other material is deposited upon the articles carried by the truck, the doors being opened and closed automatically as some part of the truck 15 meets the parts 10 and 11.

In a further travel of the truck is passes successively under the other nozzles of the pipe 35 until having arrived at the far end 20 of the housing and having passed from beneath the last of the nozzles the truck is held by the dog 26 on the inclined track.

The belt-chain or belt 39 is preferably given a slower rate of travel than the chain or belt 19 so that the truck, which it is to 25 remove from the housing, will have had ample time to properly drain.

As it passes beneath the nozzles the load of articles is so drenched that every portion thereof becomes thoroughly covered with 30 the painting material. The length of time the articles are permitted to drain depends, of course, upon the fluidity and character of the material used.

In assisting the liquid to search throughout 35 out the material upon the truck and reach every surface thereof the said truck is preferably tipped sidewise as shown in Fig. 5, while traveling upon the downwardly inclined track, Fig. 1, the deposited material 40 from the nozzles flowing over and between the articles, being discharged into the trough 3. This tipping is done by making one rail higher than the other, as shown.

In order that the truck will not be permitted to turn over I provide a guard-rail 46, clearly shown in Fig. 7. This is at a 45 higher level than the rails and is spaced outward from one of them and lies parallel to it, being supported in any suitable manner.

On some portion of the truck, such as one of the wheel journals, is a projection 47 which, in the position shown in said Fig. 5, engages beneath said guard-rail. In this 55 manner any degree of tip may be imparted to the truck without that member tipping over.

In passing from the guard-rail the truck then assumes its normal upright position 60 until having reached the far end or delivery end of the housing, it is tipped in the opposite direction being sustained in that position by a similar guard-rail 48 at the opposite side of the truck, the rail at that side 65 being raised higher than the other.

Articles of wood or any other material, or castings, may thus be treated in a continuous manner, the length of the track and the timing of the movement of the trucks through the chains or belts being such that 70 each load will be carried into the housing, drenched, and then thoroughly drained before being delivered at the far end ready for the assembling department of the plant. Other means of manipulating the trucks and 75 other means of carrying them may be readily adopted and any other means may be used than that described for tilting them for draining purposes.

The housing 4 is merely provided as a 80 safety measure as has been stated herein but, in practice, it may not be used.

In Fig. 10, and following, is shown a form of apparatus for immersing the truck and its contents, the housing being indicated 85 at 4'. The track 49 for the truck being indicated at 50 is inclined downwardly into a trough 51 deep enough to submerge the contents on the truck. If these articles are of wood they may be prevented from floating by caging them or by tying them upon the truck.

52 is a chain or belt corresponding to 19 of the earlier figures, the upper stretch of which lies between the rails as before and 95 carries the upstanding finger or fingers 53 to engage the depending portion 49², for example, on the truck. 54 indicates suitable wheels to support said upper stretch and 55 indicates the grooved rail for the truck 100 corresponding to 18 in the other figures.

At 56 is a dog to engage one of the wheels 49' of the truck, for the purpose before described, and this dog is pivoted to the rail at 57. 58 is a limiting stop and 59 105 is a spring to hold the dog in its normal or raised position to receive the truck wheel, it being observed that in Fig. 10 the truck after having been immersed is lodged upon the inclined rail near the exit end of the 110 housing where it may drain for a proper length of time.

On the truck is a projection 60 corresponding to 47 of the earlier figures, and 61 is a chain or belt running over suitable 115 wheels, one of which is shown at 62, provided with a finger 63 to engage said finger 60. As before, the chain or belt 52 delivers the truck behind the stop upon the inclined track and the chain or belt 61, which 120 is designed to travel at a slower speed than the chain or belt 52, removes the truck after having been properly drained.

It is understood, of course, that the trucks are placed in position to be engaged by the 125 finger 53 only as required. That is to say, depending upon the speed of travel through the trough 51, it is not intended that the truck being submerged will not follow too quickly the one being drained unless indeed 130

provision is made upon the inclined track for storing several of the trucks during the draining period.

In addition to the said inclined track where the draining takes place, as shown in Fig. 12, one of the rails 50 may be higher than the other so that the fluid can drain in two directions.

In lieu of tilting the truck bodily I may merely tilt its platform for draining purposes, or I may so mount the load upon the platform that it may be tilted irrespective of the truck and its platform thereby meaning to make clear the fact that it is my desire and intent to provide any means by which the articles to be treated can be handled in any way so that their thorough coating with the paint and their proper drainage will be assured.

As an example, the articles may be suspended in a basket from an overhead track arranged in a manner similar to the tracks 1 and 50 so that the tilting of the articles is accomplished.

The trucks may be moved along the track by hand, if desired, but the automatic feature is, of course, preferable.

Having thus described my invention, I claim:

30. 1. In an apparatus for the purposes described, in combination, a wheeled carriage for containing articles to be treated, a track arranged whereby the said carriage in passing over it will be tipped in all directions, and means for conveying a treating material and discharging it upon said articles.
35. 2. In an apparatus for the purposes described, in combination, a track, a carriage arranged to travel upon the same and tilted thereby to various positions in its passage over it, said carrying articles to be treated, means to move the carriage, and means for conveying a treating material along above the track and for discharging it upon the articles in the various tilted positions of the carriage.
40. 3. In an apparatus for the purposes described, in combination, a support, a carriage arranged to travel thereon for carrying articles to be treated, said support being arranged whereby to tilt the carriage and its contents, and means for carrying a treating material and discharging it upon said articles.
45. 4. In an apparatus for the purposes described, a support, a carriage arranged to travel thereon, said support being arranged whereby to tilt the carriage and its contents, means for carrying a material and discharging it upon the articles, and means for moving the carriage along said support.
50. 5. In an apparatus for the purposes described, in combination, a track and a carriage to travel thereon for containing articles to be treated, said track having its rails

inclined upwardly and downwardly whereby in its travel the carriage will be inclined endwise first in one direction and then in the other, said rails also being higher and lower with respect to one another whereby the carriage will be tilted sidewise first in one direction and then in the other, and means to convey a treating material, the same having discharge nozzles disposed at various positions along the track adapted to discharge the material upon said articles.

6. In an apparatus for the purposes described, a supporting track, a carriage arranged to travel thereon for containing articles to be treated, means to automatically engage and move the carriage along the track and automatically disengage therefrom leaving said carriage at a predetermined point, a conduit containing the coating material and for discharging it upon the articles, and other means to engage and move the carriage from said predetermined point.

7. In an apparatus for the purposes described, a carriage for containing articles to be treated, a supporting track therefor whose rails are arranged to cause said carriage in its travel to tilt in each of several directions at different places along said track, means to engage and propel the carriage and deposit it at a given position in its travel, other means to engage and propel it from that position, and a conduit for carrying and for discharging a coating material upon the articles.

8. In an apparatus for the purposes described, a supporting track, a carriage arranged to travel upon said track for carrying articles to be treated, a conduit for a liquid material includning a series of nozzles suspended above the path of travel of the truck and its contents, means to continuously supply said conduit with a flow of said material, means to engage and move the carriage part of its travel along its track and discharge it, and other means to engage the carriage and continue its movement.

9. In an apparatus for the purposes described, a supporting track, a carriage arranged to travel upon the same for containing articles to be treated, said track being inclined longitudinally throughout a part of its length whereby to tilt the carriage, and means carrying a coating material and discharging it upon said articles.

10. In an apparatus for the purposes described, a supporting track, a carriage arranged to travel upon the same for containing articles to be treated, said track being inclined longitudinally throughout a part of its length, and one of its rails being higher than the other throughout a part of its length whereby to tilt the carriage, a container for a coating material and means for causing its discharge upon said articles,

and means to move the carriage along its track.

11. In an apparatus for the purposes described, a supporting track, a receiver beneath the same for a liquid coating material, a carriage supported upon the track and movable along the same, a conduit including a series of discharge nozzles overhanging the path of travel of the carriage, means to supply the conduit with a steady flow of material from said receiver, the said supporting track being inclined longitudinally throughout a portion of its length for tilting the carriage, a portion of one of its rails being higher than the other.

12. In an apparatus for the purposes described, a supporting track, a receiver beneath the same for a liquid coating material, a carriage supported upon and movable along the track, means to move the carriage, a conduit including a series of discharge nozzles overhanging the path of travel of the carriage, and means to supply the conduit with a steady flow of material from said receiver, the said track being inclined longitudinally throughout portions of its length for tilting the carriage, sections of one rail being alternately higher and lower than the corresponding sections 30 of the other rail for tilting the carriage in its passage over it.

13. In an apparatus for the purposes described including a supporting track, a carriage for containing articles to be treated arranged to move along upon said track, means to automatically engage and propel the carriage a predetermined distance, a stop to automatically engage and hold the carriage after the travel imparted to it, other means for automatically engaging and withdrawing the carriage from said stop,

and a part for containing a material for depositing it upon said articles.

14. An apparatus for the purposes described, including in its construction, a track, a carriage supported thereon for containing articles to be treated, a dog in the path of the carriage, a traveling member to engage and move the carriage along the track into engagement with said dog, a second traveling member moving at a slower speed than the first adapted to engage and move the carriage and move it away from said dog, and means containing a liquid material and for depositing it upon the articles during their travel.

15. An apparatus for the purposes described including in its construction a track, a carriage to travel thereon for containing articles to be coated, said track being constructed thereby to tilt the carriage in any one of several directions, means lying adjacent the track for preventing the carriage overturning while in its tilted positions, the same lying in position to be engaged by said carriage, a receptacle for containing a coating material and for depositing such material upon the articles, means to automatically engage and propel the carriage to a predetermined position along the track and then release it, a dog to automatically engage and hold the carriage when released, and a second means to automatically engage and move the carriage to a new position upon the track.

In testimony whereof I affix my signature in presence of two witnesses.

JULIUS E. KARL.
